B. H. ABERNATHY,
SAFETY ROLLER BEARING SWIVEL WRENCH,
APPLICATION FILED APR. 15, 1920.

1,383,274.

Patented July 5, 1921.

UNITED STATES PATENT OFFICE.

BENJAMIN H. ABERNATHY, OF TULSA, OKLAHOMA, ASSIGNOR OF ONE-THIRD TO
WALTER S. LEE AND ONE-THIRD TO RALPH MAINES, BOTH OF TULSA, OKLA-
HOMA.

SAFETY ROLLER-BEARING SWIVEL-WRENCH.

1,383,274.

Specification of Letters Patent.

Patented July 5, 1921.

Application filed April 15, 1920. Serial No. 374,216.

To all whom it may concern:

Be it known that I, BENJAMIN H. ABERNATHY, a citizen of the United States, residing at Tulsa, in the county of Tulsa and State of Oklahoma, have invented certain new and useful Improvements in Safety Roller-Bearing Swivel-Wrenches, of which the following is a specification.

The tool to which my invention relates is an oil-field swivel wrench which is used for holding and conveying heavy drill bits and screwing them into and unscrewing them from the socket in the end of the stem at the end of the drill cable. Such a tool usually comprise a yoke with a long handle and adapted to be suspended where the yoke and handle join, a head pivotally carried by the yoke, and a jaw revolvably carried by the head and holding the bit by its squared and shouldered upper end.

The object of my invention is to provide in such a swivel wrench, a roller bearing element between the head and the jaw in order to eliminate the friction and thus make easy the rotating of the bit while held up by the wrench; a further object is to provide a safety element in such a swivel wrench which is simple in construction and not in the way and which is adapted to prevent the bit from accidentally slipping out of the jaw; further objects are as herein-after set forth.

My invention comprises certain elements and combinations including tapered roller bearings between the head and the jaw members, a novel safety element, and the parts, improvements and combinations hereinafter set forth and claimed.

In the drawings accompanying and forming part of this specification and in the description of the drawings, I have shown my invention in its preferred form and what I deem to be the best mode of applying the principles thereof; and it is to be understood that, within the scope of the appended claims, I contemplate changes in form, proportions and materials, the transposition of parts and the substitution of equivalent members, without departing from the spirit of my invention.

Figure 1 is a plan view, the handle or lever being broken away and concealed parts being shown in dotted outline. Fig. 2 is a vertical sectional elevation on a plane indicated by the line 2—2 in Fig. 1. Fig. 3 is a

front view of the jaw, detached, the left half being shown in section on a plane indicated by the line 3—3 in Fig. 1.

Similar reference characters indicate similar parts throughout the several drawings. 60

The two arms 4, 4 of the yoke are formed with lips 5, 5 so as to form a socket for receiving the end of the lever handle 6, and the yoke members and the lever are rigidly held together by the bolts 7 and 8, the latter of which forms also a means for pivotally securing the yoke to the clevis 9 by which the tool is suspended.

11 is the head formed with oppositely extending gudgeons 10, 10 whereby it is pivotally mounted in the yoke. The head is circular in form and is provided with an annular channel 12 opening upwardly and a number of tapered roller bearings 14, 14, 14 are mounted within the channel on pins 13, 75 13, 13 which span the channel. As shown in the drawings a segment of the head is removed in order to admit the bit to be passed into the center of the jaw and also in order to permit the assembly as hereinafter explained. 80

15 is the jaw member formed with a vertical central opening 16, a gap 18 to admit the bit to the central portion, and an annular channel 17 opening outwardly and formed to receive the head. The under surface of the upper flange is tapered, as shown at 19 to conform to the taper of the bearing rollers, and it is this tapered surface which supports the jaw on the head. The taper 90 is correctly formed so that there will be no slipping of any portion of the contacting surfaces between the roller and the jaw.

20 is a plate secured to the top of the jaw member by means of cap-screws 21, 21, 95 21. Several of these plates are usually provided of different sizes of slots 22 in order to make the swivel wrench applicable to different sizes of bits. They are interchangeable and supplemental to the jaw 100 member proper. The plate is circular and its rim is rabbeted to receive the lip of the safety ring 25, as shown at 24, said ring being rotatably mounted on said jaw and held thereon by means of said rabbet and 105 lip. The ring is formed with a gap, as shown at 26, to admit the bit to the middle portion of the jaw; and the gaps in the ring and in the jaw substantially correspond in width and form the maximum limit to the 110

size of the squared portion of the bit to which the tool is applicable. The ring is formed with handles 27, 27 by which it may be rotated on the jaw.

5 Projecting downwardly and outwardly from the jaw member are the handles 28, 28 whereby the attendant rotates the bit and jaw with respect to the head.

The tool is of metal and the bearing rollers are preferably of brass. Preferably, too, the jaw member proper is integrally made, and the gap in the head is sufficiently wide to permit it, without the roller bearings, to be assembled with the jaw by inserting the head from one side of the jaw, first getting one horn of the head inside one horn of the jaw and then turning the head back so it falls into proper place; the pins and rollers are then put in place, one at a time, 20 at the gap in the jaw. The assembling of the other parts is self explanatory.

The tool is used in the main about as other tools of similar general character. The gaps being in register, as shown in the drawings, the tool is applied to the squared portion of the bit immediately under the shoulders, and the safety ring is given a turn to span the gap of the jaw. The tool and bit may then be hoisted by a support applied to the clevis, an attendant holding it and guiding it by means of the long handle lever; when the bit is conveyed to position under the stem socket into which it is to be screwed, it is raised to initial engagement by means of the long lever, and then, by means of the handles 28, 28, another attendant rotates the jaw and with it the bit and screws the latter into the socket while the bit is supported by the wrench, as 40 tight as he can; the big wrenches with longer leverages are then applied to make the connection as tight as possible. To remove the wrench, the safety ring is turned to register with the gap in the jaw and the 45 gap in the jaw is brought to register with the gap in the head, and the tool is withdrawn.

The function of the roller bearings and the safety ring will be appreciated in view 50 of the fact that drill bits now used in oil-field work weigh up to 2,000 pounds and more.

Having thus described my invention, what I claim is:

1. The combination of a yoke formed with 55 a lever handle and means for suspending same, a head pivotally mounted in the yoke and formed with an annular channel opening upwardly, pins mounted in said head and spanning the channel, tapered bearing 60 rollers mounted on said pins, a jaw member formed with a vertical central opening and a gap thereto and also formed with an annular channel opening outwardly, said head revolvably fitting within said channel of said 65 jaw member, the under surface of the upper wall of said last named channel being tapered and being supported on said rollers, a clamping plate mounted on the top of said jaw member, cap-screws securing said plate 70 to said jaw member, said plate being formed with a slot for receiving and supporting a drill bit and being also formed with an exterior annular rabbet, and a safety ring having an annular lip engaging in said rabbet and rotatably mounted on said jaw member and also formed with handles and with a gap, said head being also formed with a 75 gap.

2. In a swivel wrench, the combination of 80 a head member, means for pivotally supporting said head member, a jaw member formed with a gap and revolvably mounted on said head member, a clamping plate secured on top of said jaw member and formed 85 with a slot for receiving and holding a drill bit, and a safety ring formed with a gap and rotatably mounted on said jaw and adapted in one position to register its gap with the jaw gap and in shifted position to 90 span the jaw gap.

3. In a swivel wrench, the combination of 95 a head member, means for pivotally supporting said head member, a jaw member revolvably mounted on said head member and formed with an opening for receiving and supporting a bit, and a safety ring formed with a gap and rotatably mounted on said jaw member for closing and opening the jaw opening.

In testimony whereof I have hereunto affixed my signature.

BENJAMIN H. ABERNATHY.
